UNITED STATES PATENT OFFICE

WILLIAM HARRY CLIFF, OF TERRE HAUTE, INDIANA, ASSIGNOR TO TERRE HAUTE BOILER WORKS COMPANY, OF TERRE HAUTE, INDIANA, A CORPORATION OF INDIANA

STEEL BOILER

Application filed October 26, 1928. Serial No. 315,219.

My invention relates to improvements in heating boilers and particularly to the sectional type of heating boiler wherein the boiler is formed of a plurality of sections arranged one behind the other, the front and rear sections forming end sections through which firepit openings and clean out openings are provided, as well as smoke flues, etc., and the intermediate sections when assembled are provided with an arch having water legs extending downwardly on each side and forming the fire pot.

Heretofore such boilers have always been constructed of cast iron due primarily to the impracticability, especially from a commercial standpoint, of forming the sections in any other manner than that of casting.

It is one object of my invention to construct a boiler of the sectional type from steel, preferably sheet steel. The boiler is constructed in such a manner that the various sections may be drawn or pressed from plate or sheet steel of suitable thickness. I have found from experiment that these boilers may be readily and comparatively cheaply made and that they are superior to the cast iron sectional boiler. One objection heretofore present in the cast iron boiler is that the sections being formed of cast iron are quite liable to crack, either in placing the sections in position or after they have been positioned. Furthermore, cast iron as compared to steel has relatively small tensile strength and as a result cast iron heating boilers necessarily carry extremely low steam pressure. While it is not essential for heating purposes in all cases that relatively high pressures be carried, it has been found that under certain circumstances comparatively high pressures are desirable. I have also found from experiment that the boiler of my invention has a very high efficiency from a steaming standpoint and is capable of generating steam with a minimum fuel consumption and in an extremely short time

after the initial firing. Obviously, the walls of a boiler formed of sheet steel may be of materially less thickness than the walls of cast iron boilers and it is partially to this thin wall that I attribute the rapid and efficient steaming qualities.

It is another object of my invention to provide a sectional boiler of such a structure that it shall consume a minimum quantity of fuel and have a high efficiency from a steaming standpoint.

For the purpose of disclosing my invention I have illustrated one embodiment thereof in the accompanying drawings in which Fig. 1 is a front elevation of a boiler embodying my invention; Fig. 2 a side elevation thereof partly in section; Fig. 3 a rear elevation thereof; Fig. 4 an enlarged sectional view of the front section; Fig. 5 an enlarged sectional view of the rear section; Fig. 6 an enlarged sectional view of an intermediate section and Fig. 7 a transverse enlarged sectional view of an intermediate section.

In the embodiment of the invention illustrated, the boiler comprises the front section 1, the rear section 2 and intermediate sections 3 which may be provided in any number depending upon the size of the boiler desired. The front section is formed hollow to provide the necessary water space as is usual in sectional boilers and has a smoke flue opening 4, firing door opening 5 and ashpit opening 6. This section is formed of two plates, the front plate 7 and rear plate 8. The outer edges of these plates are turned inwardly to provide inwardly extending flanges 9 and 10 which, when the two plates are placed adjacent one another, abut. Similar flanges 11 are turned in around the cleanout opening 4, and 12 around the firing opening 5, and 13 around the ashpit opening 6. The abutting flanges are secured together in any suitable manner along the abutting line and I have found that the most satisfactory manner of connect-

ing the flanges together is by welding the same. After the abutting flanges have been welded together the two plates form a complete front boiler section integral to all intents and purposes as the weld along the line of joint is such that the metal is fused. This section at its top is provided with a nipple opening 14 by which it may be connected to a suitable supply line and with a nipple opening 15 through which a suitable nipple connection is made with the next succeeding section. This connection will be described more fully in detail hereinafter.

By drawing the flanges 9 and 10 and 11, 15 12 and 13 on the back and front sheets, the sheets are not only spaced apart to form a hollow section when they are connected together, but are also braced thoroughly against buckling. With such a wide expansion of 20 flat surface, unless these plates were braced in some manner there would be a tendency for them to buckle or bulge under the pressure developed inside and by the flanged arrangement the faces of the plates are sufficiently braced and strengthened to insure 25 against buckling.

It will be noted that the ashpit opening is formed substantially in the form of an arch, thereby providing on each side of the opening a pair of water legs 16 provided on their front faces with cold water inlet openings 17 and on their rear faces with connection nipple openings 18. These openings are provided with connecting nipples connecting the legs of the front section to the legs of the next adjacent section and these nipples are constructed in exactly the same manner as those used for connecting the top of the sections together.

40 The back section 2 is also constructed of a pair of front and back plates 19 and 20 having formed thereon at their outer periphery inturned flanges 21 and 22 in a manner similar to the front section. This back section is provided with a smoke flue opening 23 and with a bottom draft opening 24 leading to the ashpit. Each plate around the smoke flue opening is provided with an in-turned flange 25. These flanges are not quite 45 as deep as the flanges 21 and 22 and are connected together by suitable tubular sections 26 which telescope the openings and fit tightly within the flanges 25. After having been placed in position the tubes are welded to the flanges to make a tight joint at this point. It will be understood of course, that the flanges 21 and 22 as well as the flanges 27 50 around the ashpit opening 24 are welded together at their abutting points in the same manner as has been described with respect to the front section. The front plate 19, at a point intermediate of its top and bottom is also provided with a flue recess 28 which is preferably formed by providing an opening 55 in the face of the plate 19, which opening

is surrounded by an inturned flange 29 and telescoping this opening is a dish-shaped filer 30 which is welded as at 31 to the flange 29.

The object of this recess will appear more fully hereinafter. The rear wall of this plate 30 may be additionally braced by means of stay bolts or braces 32 which extend between this rear wall and the rear plate 20, being welded at their ends to both plates. The front plate is provided at its upper end with a suitable nipple opening 33 and with an outlet opening 34 having an internally threaded sleeve 34'. This outlet opening 34 permits of the manipulation of the nipple connections and after the connections have all been made, may be suitably closed by a threaded plug. Likewise, the bottom legs are provided with nipple openings 35 for connection with the legs of the intermediate sections and with outlet openings 36 for connection to the water supply for the boiler in the event it is desired to make connection at the rear of the boiler instead of the front.

Each intermediate section comprises a front and back plate 37 and 38 respectively. Each plate is provided with flue openings 39 and with a fire pot arch opening 40. It will be noted that this arch opening is curved at its upper portion as at 41 which curve meets the substantially straight sides 42, which in turn merge in an inwardly extending curve as at 43 to provide the increased width as at 44, thereby providing a fire arch opening having, when the section is completed, downwardly extending water legs on each side of the fire arch, which water legs are enlarged at their bottom. This fire arch opening is provided with a peripheral flange 45, it being understood that the front and back plates are constructed in exactly the same manner, and each of the fire tube openings 39 is surrounded by an inturned flange 46, the flanges 46 being slightly less in depth than the flange 45. The flanges of the fire arch opening of each plate are connected together by a band 47 which telescopes the flanges 45 and is welded thereto. This flange extends to the bottom of the leg and terminates at the point 48. An outer band 49 connects the in-turned outer flanges 50 of the two plates 37 and 38, being welded to the inturned peripheral flange 50 of each plate and this band extends to the bottom, meeting the fire arch band at the point 48. At the junction point reinforcing rib 51 is welded in position. It is thus seen that a hollow section, greater in width than the front and rear sections is provided. The fire tubes are preferably formed of tubular members 52 which telescope the flanges 46 of the fire tube openings and are suitably welded at their junction to the flanges.

Each of the front and rear plates in the water legs is provided with nipple openings 53 at both front and rear and each of the

front and rear plates at that part forming the steam dome is provided with nipple openings 54.

Suitable side braces 55, 56, 57 and 58 preferably formed of angle or bar irons extending longitudinally of the sides of the section are welded in position and serve as additional bracing for the sections. The braces 57 and 58, it will be noted, are arranged in the water legs on each side of the fire pot and are disposed substantially opposite the top and bottom of the straight portion 42 of the legs, thereby considerably narrowing the space between the legs and angles. The purpose of this will appear more fully herein-after.

Grate lugs 59 for supporting the grates are secured on the inner face of the fire arch adjacent the lower ends of the water legs.

The sections are assembled, one behind the other, and the sections are connected together by suitable nipples. Each of these nipples comprises a tubular member 60 which extends through the nipple opening and is provided with an annular flange 61 bearing against the inner wall of the opening. The member extends through the wall of the next adjacent section and between the two sections there is placed a suitable washer 62. Adjacent the wall of the next succeeding section is an internally threaded nut 63 which screw threads on the tubular member 60 and by drawing this nut up tightly the sections are secured together. These nipple connections are made at the top and in each of the water legs so that the sections will all be connected together at the bottoms of the water legs for the circulation therethrough of the cool water, and at the top of the steam dome for the passage therethrough of the steam generated.

It will be understood of course, that suitable openings are provided at desired places for the securing in position of gages and the like.

When the sections are assembled the smoke flue opening 4 of the front section overlaps the top and bottom row of flue openings 39 of the intermediate sections and the flue recess 50 28 of the back section overlaps the fire pot arch, and the bottom flue openings of the intermediate sections, while the smoke flue opening 23 coincides with the top row of the flue openings 39. Therefore the smoke and heat travel from the fire pot rearwardly up through the flue recess 28, thence forwardly through the bottom flue openings 39, upwardly through the flue opening 4 of the front section and then rearwardly through the top row of flue openings and out through the flue openings 23 of the rear section.

I have found that due to the narrowing of the space in the water legs of the sections by means of the angles or bars 57 and 58, and due to the narrowing of the water legs at this

point, very rapid steaming is effected. The colder water lies in the enlarged bottom portions of the water legs. The heat from the fire rapidly heats the side walls of the fire arch as well as the top dome thereof and a rapid acceleration of the upward movement of the water in the water legs results from the narrowing of these legs by the braces 57 and 58. This accelerated movement of the water and spreading of the same into a comparatively thin film adds materially to the rapidity with which the water is heated. The accelerated movement of the water over the firepot wall wipes off the "dead film" of water lying against this wall so that the thermo resistance is reduced to the minimum.

It will be noted that the side braces 55, 56, 57 and 58 extend longitudinally of the section, well inclined from the horizontal and their ends are spaced apart from the ends of the section. The angle braces on each side of the boiler are inclined in the same direction. As a result of this inclination or sloping of these braces when the boiler is generating steam a circulating movement of the water is imparted, the water tending to flow upwardly along the upward inclination of the braces to the steam dome, whence the steam escapes therefrom and the water having a tendency to flow downwardly at the opposite end of the boiler section. This increases the heat exchange through the boiler shell, causes quicker release of the steam and results in a more nearly constant water line, both under maximum and minimum steam demands and gives a dryer steam than has heretofore been accomplished. As a result of this inclination of the braces, which constitute baffles or fins, a positive movement in a definite direction is imparted to the water when the boiler is in operation.

I claim as my invention:

1. A sheet metal sectional boiler comprising a plurality of sections including an intermediate section comprising front and back sheets, each sheet having its lower portion cut out to form a fire arch opening and having openings in its upper portion to form flue openings, the edges of the sheets being inturned to form peripheral flanges facing one another, the edges of the material surrounding said fire arch opening being inturned to form peripheral flanges, tubular flues interposed between the front and back sections connected thereto and surrounding said flue openings, a connecting member extending between the edge flanges and second connecting member connecting the edge flanges of the fire arch opening whereby a hollow section is formed provided with suitable flue openings extending therethrough and having a fire arch opening enclosed on each side by water legs.

2. A sheet steel sectional boiler comprising a plurality of sections including an in-

termediate section comprising front and back sheets, each sheet having its lower portion cut out to form a fire arch opening and having openings in its upper portion to form flue openings, the edges of the material surrounding said openings being inturned to form peripheral flanges, tubular flues interposed between the front and back sections and connecting the flanges surrounding the flue openings, a connecting member extending between the edge flanges and a second connecting member connecting the edge flanges of the fire arch opening, whereby a hollow section is formed provided with suitable flue openings extending therethrough and having a fire arch opening enclosed on each side by water legs.

3. A sheet steel sectional boiler comprising a plurality of sections adapted for side by side arrangement and including an intermediate section comprising a front and back sheet, each sheet having a plurality of openings extending therethrough near its top to provide flue openings and having an arched opening at its bottom, said opening being so shaped as to form legs comparatively narrow intermediate of the top and bottom and widening at the bottom, the edges of said sheet and the edges surrounding said openings being turned at an angle to the sheets to form peripheral flanges, flue tubes extending between the front and back sheet and connecting the flanges surrounding the flue tube openings, an outer band connecting the outer peripheral flanges, an inner connecting member connecting said fire arch opening flanges, whereby a hollow section is formed having a steam dome extending downwardly on either side of a fire arch in the form of water legs relatively narrow in cross section at the sides of the fire arch and increasing in width at the bottom.

4. An intermediate section for sectional boilers having a steam dome and a firepot arch and water legs extending downwardly on each side of said arch, said legs being smaller in area on each side of the arch and increasing in area at the bottom, and baffle members in said legs opposite the sides of the firepot arch for forming restricted openings for the passage of the water upwardly through the leg.

5. A sheet steel boiler section comprising a front and back sheet, each sheet having its edges turned at an angle thereto to form a peripheral flange, the flanges of the two sheets forming the sides, bottom and top of the section and braces welded to the inner faces of the sides and extending longitudinally of the section.

6. A sheet steel boiler section comprising front and back sheets each having its edges turned at an angle thereto to form a peripheral flange, the flanges of the two sheets facing one another and an intermediate con-

necting band connecting said flanges, the flanges and band forming the top, bottom and sides of the section, and a plurality of braces secured to the inner faces of the sides and extending longitudinally of the section. 70

7. A sheet steel boiler section comprising front and back sheets, each sheet having its lower portion cut out to form a fire arch opening having extending downwardly on each side water legs, the edges of each sheet being turned at an angle thereto to form a peripheral flange, the flanges of the two sheets facing one another and connecting members connecting said edges and secured thereto, said flanges and connecting members forming the sides and top of the section and the inner sides and top of the arch and braces secured to the inner faces of the sides of the sections in the water legs and extending longitudinally of the section. 75

8. A hollow boiler section having a steam dome and firepot arch and water legs extending downwardly on each side of said arch, and baffle members in said legs opposite the sides of the fire arch extending longitudinally of the section and inclined from the horizontal, said baffle members being spaced apart from the front and rear of the section. 90

9. A sheet steel boiler section comprising a front and back section, each sheet having its edges turned at an angle thereto to form a peripheral flange, the flanges of the two sheets forming sides, bottom and top of the section and braces secured to the inner faces of the sides extending longitudinally of the section and being inclined from the horizontal, said braces being spaced from the front and back plates of the section. 95

10. A sheet steel boiler section comprising front and back sheets, each sheet having its edges turned at an angle thereto to form a peripheral flange, the flanges of the two sheets facing one another, and an intermediate connecting band connecting said flanges, the flanges and band forming the top, bottom and sides of the sections and a plurality of braces secured to the inner faces of the sides, extending longitudinally of the section and inclined from the horizontal, said braces being spaced apart from the ends of the section. 100

11. A sheet steel sectional boiler comprising a plurality of sections including an intermediate section comprising back and front sheets, each sheet having its lower portion cut out to form a fire arch opening, and having openings in its upper portion to form flue openings, the edges of the sheets being inturned to form peripheral flanges facing one another, the edges of said material surrounding flanges facing one another, the edges of said material surrounding said fire arch opening and flue openings being inturned to form peripheral flanges, tubular flues interposed between the front and back sections and overlapping the flanges of the 115

flue openings, a connecting member extending between the edge flanges and a second connecting member extending between the edge flanges of the fire arch opening, said members overlapping the flanges and welded thereto.

5 In witness whereof, I have hereunto set my hand at Terre Haute, Indiana, this 19th day of October, A. D. one thousand nine hundred and twenty eight.
